UNITED STATES PATENT OFFICE.

GEORGE BENJAMIN, OF GARDNER, MASSACHUSETTS, ASSIGNOR TO
PHILANDER DERBY, OF SAME PLACE.

IMPROVEMENT IN MORTISING AND TENONING MACHINES.

Specification forming part of Letters Patent No. 174,184, dated February 29, 1876; application filed
January 26, 1876.

To all whom it may concern:

Be it known that I, GEORGE BENJAMIN, of Gardner, in the county of Worcester and State of Massachusetts, have invented certain new and useful Improvements in Mortising and Tenoning Machines; and I do hereby declare that the following is a full, clear, and exact description thereof, which will enable others skilled in the art to which it pertains to make and use the same, reference being had to the accompanying drawing, and to the letters of reference marked thereon, which form a part of this specification.

This invention relates to the forming of tenons on the legs of rocking-chairs, and at the same time on another part of the frame to bore the mortises in the rockers for the same, the two operations being performed by the same motive power, as will be more fully hereinafter described.

Figure 1 represents a plan view of the top of the machine. Fig. 2 is an elevation of one side.

A A represent the frame, upon which the working parts are arranged, and which is supported on four legs, A' A'. B is a main shaft, placed under the frame athwart the same, and supported in suitable bearings on the longitudinal pieces A'', extending between the posts A' A'. On this shaft B are placed the several pulleys to communicate motion to the rotary cutters and boring-tools above, by means of properly-arranged belts, in the usual and obvious manner, whereby these cutters and boring-bits will duly perform their proper functions, as will be explained. B' is a pulley, on which are belts b b' b''. (Seen in Fig. 2.) Other belts, as e e' e'', can be seen in Fig. 1, and will be explained hereafter. The belt b is twisted to give a rotary motion to the vertical arbor C, on which is a cutter-head, c, above the frame. b' is a belt extending to a leading-pulley, d, (shown in dotted lines in Fig. 2,) and thence up to and over a pulley, d', on a horizontal arbor, carrying at its outer end a cutter-head, f'; above this is a similar arbor and cutter-head, f''. Around the pulley d'' of this latter arbor, and over another pulley, d''', the belt b' is carried, and thence down to a leading-pulley, d''', and to the main pulley B'.

These arbors are supported in standards H H on the frame, and are regulated by a screw, h, on top. By this belt the cutter-heads f f' travel in opposite directions. On top of the frame, and pivoted to a bracket, D, is a vibrating table, D', which travels over an arc, D'', on the frame, and on which is to be placed the chair G, as represented in dotted lines in Fig. 1, the lower legs g g' projecting beyond the arc of the circle (whose center of motion is at the pivot a) as much as the length of tenon is required. The lateral motion of the table D' to the left will bring these legs between the cutter-heads f f', and dress them to the proper thickness for the tenons; the lower cutter being double, the outer half takes the post out of wind. The left leg g will come up to the vertical cutter-head c, which will corner the tenon g, and when the table is carried to the right the leg g' will reach to a corresponding cutter-head, c'', which will corner the tenon g'. This cutter-head is on the top of a vertical arbor, C', which is driven by a belt, b'', from the main shaft B, as seen in Fig. 2, the arbor and pulley being shown in dotted lines. The chair is kept in position by a clamp, h', operated by an eccentric lever, e. To the under side of table D' is attached, by a pivot at i', a metallic strap, i, which extends to a sliding frame, I, on the other side of the main frame. This strap i is fastened to the under side of frame I, so that as the table D' is moved on its pivot a, either to the left or right on the arc D'', the strap i moves in the corresponding small arc, (shown in dotted lines x x,) and consequently has an endwise movement corresponding to the versed sine of that arc, and draws inwardly the table I, and removes the same to its original position, as the table D' vibrates the other way to the position shown in Fig. 1. On table I are two horizontal arbors, K K', having pulleys l l', on which are belts e' e'', leading from the main shaft B under the frame. In the ends of these arbors are two boring-bits of proper size, socketed, so that they may be removed for different sizes of bits.

In the frame I is another sliding frame, I', carrying arbor K' and pulley l', driven by belt e'', as before described. Attached to

sliding frame I' is a rack-bar, *m*, which works with its cogs into a long spur-gear, *n*, on a shaft, *n'*, operated by a wheel, *n''*, outside of the frame A, the inner end being supported by a bearing at *o*. Over this rack-bar *m* is a guard *m'*, (shown in dotted lines,) which keeps the rack-bar to its vertical position, while it can move laterally with the frame I, in or out, as table D' may carry it, the upper wheel *n* being made long to admit of this movement laterally.

The sliding frame I', which is operated by the rack-bar and the spur from the wheel *n''*, is to adjust the boring-bit *p'* to such a distance from *p* as to gage precisely with the distance between the tenons on legs *g* and *g'*, the bit *p* being always stationary.

In the middle of the main frame A, and between frame I and table D', is a sliding frame, *J*, supported by guides *j j'*. This slide is attached, by an elbow-joint, *j''*, to a connecting-bar, *J'*, to an eccentric wheel, which is on the top of a vertical shaft, operated from main shaft B by a pulley and belt, *e*, as seen in Fig. 1. As this shaft rotates, it moves to and fro the slide *J*. On this slide is clamped a rocker, with its hollow curve to the boring-bits *p p'*, the one place for a mortise being gaged opposite the fixed bit *p*; then, by moving the wheel *n''*, the bit *p* is adjusted to the other place for the mortise. Now, as the chair, being clamped in its proper position on the vibrating table D', is moved to the cutter-heads *ff'* to cut the tenons on *g g'*, the boring-bits *p p'* are drawn to the rocker by strap *i* and the rotation of shaft B, giving motion to all the cutter-heads and boring-bits and eccentric shaft, the movement of which last causes the slide *J* to move longitudinally to the right of the figure, and carrying the rocker, (shown in dotted lines,) so that the boring-bits *p p'* make elongated mortises, and as the chair on table D' is carried to cutter-head *c*, the cutters *r r'*, above the bits *p p'*, form a "gain" on the edge of the rocker, into which the shoul-

der of the tenons *g g'* will match, thus giving a firm socket-bearing to support the tenon-and-mortise joint. The reverse motion of the table D' to the right withdraws the bits from the mortise, and the rocker can be removed and another one substituted, while the chair is turned over and the other two legs put in position.

Thus, by this arrangement of the chair, table, and the rocker sliding frame, the two operations of tenoning the legs and cutting corresponding mortises in the rockers are simultaneously performed.

Having thus described my invention, what I claim, and desire to secure by Letters Patent, is—

1. The reciprocating frame I, in combination with the vibrating table D', substantially as and for the purpose described.
2. The combination of the reciprocating frame I, vibrating table D', and reciprocating table J, substantially as and for the purpose described.
3. The combination of the vertically-moving and adjustable cutter-heads *ff'*, cutter-heads *c* and *c'*, and vibrating table D', for the purpose of forming the tenons on legs of chairs, and cornering the same, substantially as and for the purpose described.
4. The combination of the reciprocating frame I, with its adjustable slide I', the vibrating table D', reciprocating table J, the cutting tools *ff'* and *c* and *c'*, and the mechanism for operating the same, whereby the legs of chairs are tenoned and the rockers mortised coincidently and to the proper gage, substantially as and for the purpose described.

In testimony that I claim the foregoing as my own I affix my signature in presence of two witnesses.

GEORGE BENJAMIN.
